SUPPORTING STRUCTURE FOR ELEVATED
RAILWAY TRACKS AND METHOD OF ELE-
VATING THE TRACKS

Howard E. Culbertson, Cleveland Heights, Ohio

Application July 3, 1937, Serial No. 151,894

11 Claims. (Cl. 238—2)

This invention relates to a new and improved supporting structure for elevated railway tracks and to an improved method of elevating tracks, and has particular reference to the manner of 5 elevating tracks through a congested district where the right-of-way is limited.

Heretofore, in elevating railway tracks under the conditions mentioned above, i. e., through a congested district where the right-of-way is of 10 limited width and where it is essential that the tracks be elevated without interfering with the usual traffic, the method employed has been as follows: First, one of the tracks is removed and a trestle is built along the entire distance where 15 the tracks are to be elevated, this trestle being formed largely of vertical timbers or piling driven into the ground where the removed track was previously located. After these timbers are driven, the upper ends of them are cut off to 20 grade and capped, the timbers are braced, and a track is laid thereon to accommodate one line of traffic. Then, in a similar fashion, the adjoining parallel track is removed, a second trestle is built in the location previously occupied by the 25 removed track, which is then placed on top of the trestle, and the second line of traffic elevated. If the traffic system involves more than two tracks, this same operation is repeated for the 30 three or more tracks, as the case may be. After all the tracks are elevated, it has been customary to build gravity walls to support the fill and the 35 traffic, and in some instances, depending upon the character of the soil, it has been necessary to drive or place concrete piles under each gravity wall near its outer edge to withstand the overturning moment of the wall.

The fill of soil, cinders or sand and the like is dumped from the cars on the trestles and the timbers of the trestles are buried in the fill and 40 remain there, although they perform no useful purpose after the tracks have been ballasted on the fill, it being unfeasible to salvage the timbers of the trestles, except possibly the horizontal timbers on which the ties which support the tracks 45 on the trestles are laid.

The principal object of the present invention is to elevate the tracks by an improved method and to provide a supporting structure for the tracks, and for the fill on which the tracks are eventually 50 supported, which are more economical from several standpoints than the method and supporting structure heretofore employed, including a decided saving in concrete, the elimination of the necessity for trestles and the loss of timber incident thereto, the elimination of piles as a bearing 55

structure for the outer walls, a decrease in time and labor required to elevate the tracks, and less interference with traffic.

The above objects are attained by entirely eliminating the trestles and by erecting transversely of the right-of-way over the space previously occupied by one or more of the tracks, a series of piers or pier sections which with the retaining wall or walls form a permanent supporting structure for the fill and the elevated tracks, the structure, however, being built in such a way that the piers or pier sections form temporary supports for the elevated tracks until the supporting structure is completed to receive the fill on which the permanent tracks are eventually placed. In the 15 preferred embodiment of the invention I employ, in place of the trestles heretofore utilized, a series of box-type retaining walls composed of concrete piers, which are arranged at intervals transversely across the space occupied by the track or tracks 20 to be elevated, and concrete apron walls which are constructed between the ends of the piers and are so interlocked therewith that with a minimum amount of concrete in the construction of the walls they are enabled to withstand, when suitably 25 reinforced, with an ample factor of safety, the load created by the fill and by the traffic after the permanent tracks have been installed.

In accordance with my invention, the preferred 30 actual method of construction and track elevation consists, first, in building parts or sections of these piers along the length of track to be elevated; second, constructing an elevated track upon these piers, which are placed a suitable 35 distance apart, depending upon the load to be supported, and after this track is in service to use it in the construction of the apron walls between the pier ends; third, the completion of the piers by extending them across the entire width to be spanned by them, and the building of the apron 40 walls between the ends of the extended piers. After this, the necessary fill is made between the apron walls and the tracks are installed on the fill, at proper line and grade. The above method is utilized with slight modifications, regardless of 45 the number of tracks to be elevated. In case the system includes two tracks, the procedure outlined above will be followed. If there are more than two tracks, as, for example, three or four, two tracks will be removed, pier sections will be built 50 across the space previously occupied by the removed tracks, two elevated tracks will be temporarily supported thereon, the apron walls will be placed as described, and then the remaining track or tracks will be removed and the piers will 55

be completed by extending them entirely across the right-of-way, after which the fill will be supplied and the elevated tracks permanently erected on the fill. Regardless of the number of tracks, 5 while one or more elevated tracks are temporarily supported on the pier sections extending inwardly from one or both sides of the right-of-way, the remaining track or tracks, during the construction of the pier sections and apron walls, will be 10 left at their original level so as to take care of the required railway traffic.

The invention may be further briefly summarized as consisting in certain novel steps of my improved method of elevating the tracks and 15 in the details of construction of the supporting structure for the tracks and fill.

In the accompanying sheets of drawings, wherein I have shown the preferred embodiment of my invention,

20 Fig. 1 shows in plan two sections of a long series of piers which are built for the length of trackage to be elevated, the sections being of sufficient length crosswise of the right-of-way to support the first temporary elevated track;

25 Fig. 2 is a plan view of the same with the track temporarily supported thereon;

Fig. 3 is a vertical sectional view substantially along the line 3—3 of Fig. 2;

30 Fig. 4 is a view somewhat similar to Fig. 3, but showing in section the apron wall which is built between the pier ends of Fig. 1 after the track is temporarily erected on the latter, and this view showing also an adjoining track still at its original level to take care of the traffic while the other 35 track is temporarily supported on the pier sections;

40 Fig. 5 is a view similar to Fig. 4 after the structure has been completed and the two tracks permanently elevated, this view assuming by way of illustration only a two-track system;

Fig. 6 is a plan view of the box structure which is employed, this being composed of piers which extend across the right-of-way and apron walls which are constructed between and interlocked 45 with the ends thereof;

50 Figs. 7 and 8 are perspective fragmentary views, the former looking toward the inner side and the latter looking toward the outer side, these views showing particularly the arrangement and the manner of interlocking the piers and the apron walls;

Fig. 9 is a transverse sectional view through two adjoining piers with the track temporarily supported thereon;

55 Fig. 10 is a transverse sectional view corresponding to Fig. 4 showing a modification wherein in the trackage includes four parallel tracks, the two outer tracks being shown temporarily supported on the partly constructed piers;

60 Fig. 11 is a view similar to Fig. 5 with the four tracks in their final elevated position;

Figs. 12 and 13 are transverse sectional views showing a modification which may be employed in the ramp leading to the upper level to which the 65 tracks are adapted to be elevated, Fig. 12 showing the structure partly completed and Fig. 13 showing the tracks in their final elevated position at a given point in the length of the ramp;

Fig. 14 is a plan view of Fig. 12; and 70 Fig. 15 is a view similar to Fig. 12, but showing a four-track system.

The tracks to be elevated through a congested district or a portion of a town or city are usually of considerable length, and the trackage generally consists of at least two tracks and fre-

quently more than two. On the first and second sheets of the drawings a two-track system is illustrated, whereas, in Figs. 10 and 11, my improved method and track supporting structure are illustrated in connection with four parallel 5 tracks. However, the method and the principle of the structure involved in carrying out the method are the same regardless of the number of tracks.

Assuming for the moment that there are two 10 tracks only to be elevated, with my method one track is removed for the required distance, including the ramps if necessary, and the other track will take care of the traffic normally served by the two tracks. I then erect at suitable intervals, depending upon the load to be supported, for the full length or distance that the tracks are to be elevated, sections or portions 15a of reenforced concrete piers 15 which sections are eventually extended in the manner hereinafter explained to 20 form complete piers 15 shown in Figs. 5 and 6. These pier sections 15a extend from one side of the right-of-way inwardly partway across the latter a distance a little greater than the width of one of the tracks. On these pier sections 15a is placed a main track T, the other track T' (Fig. 4) being left at its original level and taking care of the main traffic until the track T can function for that purpose. The track T may be temporarily supported on the pier sections 15a in any 30 desired manner, but in this instance the ties t' are laid on steel beams t² of sufficient length to span the adjacent pier sections 15a, and these in turn are supported on the pier sections by any suitable short timbering t³.

35 After the track T is elevated but before it becomes a track to accommodate traffic, it may be used, if necessary, in the construction of an apron wall 16, the panels or sections of which are interlocked with the ends of the pier sections 15a in 40 a manner to be subsequently explained. Then the second track T' is removed and the piers 15 are completed by building onto the previously erected sections 15a sections 15b which extend across the remainder of the right-of-way and are generally 45 somewhat longer than the sections 15a first erected, as shown in Fig. 5. The two sections 15a and 15b are tied together by reinforcing bars 11 and become one unitary monolithic structure.

50 Next the second apron wall 16 is constructed along the opposite line or margin of the right-of-way, the panels or sections being between the ends of the pier sections 15b and interlocked therewith, as in the first instance. This completes the box structure illustrated in Fig. 6, 55 which, it will be understood, will be continued the full distance that the tracks are to be elevated, preferably, however, not including the inclined ramps and other situations, as will be explained presently.

60 Referring again to the box structure and certain desirable features of the piers and apron walls, the piers rest on foundations 18 and the apron walls on foundations 19, to which the piers and apron wall sections will be anchored by vertical reenforcing bars indicated conventionally at 20 in some of the figures. These foundations will, of course, be of suitable depth, depending upon the nature of the soil. The tops of the pier sections 15a and 15b are horizontal for the major portion of their length, but near the outer ends of the sections they are preferably inclined upwardly, as shown at 15c, and then horizontally to the end of the pier. The extreme outer ends are widened as shown at 15d and between the wid-

ened portions 15d and the inclined portions 15c vertical grooves 15e are provided to receive the ends of the apron walls, the interlock being clearly shown at 21 in Figs. 6, 7, and 8. The thickened ends of the piers and the notches inwardly thereof of form substantial shoulders which resist the outward movement of the sections of the apron walls under the pressure due to the fill and traffic. The shouldered outer ends of the piers are 10 suitably reenforced to resist shearing under this pressure, as indicated conventionally at 17a. It will be understood, of course, that the panels or sections of the apron walls will be suitably reinforced generally by vertical and horizontal 15 bars indicated conventionally at 22, but the details of which I have not attempted to illustrate as the amount and character of the reinforcements in any part of the structure can be made anything desired to suit the requirements. I 20 prefer, however, that the ends of the sections of the apron walls where they are interlocked at 21 with the outer ends of the piers be not tied to the piers by any type of reenforcement as the interfitting ends of the apron wall sections and 25 piers are preferably left free for expansion purposes.

The box construction of transverse piers and retaining walls of the apron type now having been completed for the full length, the fill, designated 23, is now made between the apron walls and the piers and to a suitable height above the latter, using for this purpose any kind of suitable material, such as slag, earth, or sand, after which the permanent elevated tracks designated 30 T³ in Fig. 5 are made upon this fill and ballasted at proper grade.

The above description assumes a two-track system, but, as previously pointed out, the system frequently involves more than two tracks, but, 40 regardless of the number of tracks, my improved method and form of construction, with slight modifications, can be utilized very effectively. For example, in Figs. 10 and 11, I have shown a 45 way in which a system of four tracks can be elevated by my improved method and system of piers and apron walls. In this instance, the two outer tracks are first removed and reenforced concrete pier sections 24a and 24b are built inwardly from the opposite sides of the right-of-way, and after elevated tracks T⁴ are temporarily 50 erected on these pier ends, the reenforced concrete apron walls 25 are built between the outside ends of the piers 24a and 24b along opposite sides of the right-of-way and are interlocked with the pier ends precisely as in the construction first described. Meanwhile, the intermediate track or tracks T⁵ are utilized for regular traffic 55 purposes until they are ready to be taken up and the traffic diverted to the elevated tracks T⁴. Next the tracks T⁵ are removed, after which the piers are completed by joining opposite pier ends 60 24a and 24b by adding the intermediate sections 24c. Thus the completed piers extend entirely across the right-of-way and form with the apron walls 25 box-like structures extending the full length of the track to be elevated and similar to the structure illustrated in Fig. 6, except as to the width of the oblong enclosures. Next the fill 26 65 is made between the apron walls and over the piers, as illustrated in Fig. 11, and on this fill will be constructed the permanent elevated tracks T⁷, thus completing the elevation.

Nor is this method limited to the manner of procedure set forth and described above. For 70 instance, in elevating a railway comprising three

or more tracks, any of the tracks may be elevated first as may be desired to effect economies of construction or facilitate the carrying of traffic during construction or for other reasons, leaving the other tracks to care for the traffic. For example, it is possible to first elevate the two adjoining tracks on either side of a four-track system—allowing the two remaining tracks to care for traffic; or, the two central tracks may be elevated first, leaving the two outside tracks to care 75 for traffic. In a system of more than four tracks, many modifications may be utilized to best suit the local conditions.

Thus it will be seen that the method described involves the use of piers as the supporting structure for the track or tracks while in the process of being elevated but which piers become a necessary and integral part of the finished structure in that these piers or temporary supports for the tracks are so designed and constructed that 80 after the earthen fill has been made between the outer apron walls and after the tracks have been located on the fill they become continuous members extending transversely across the space occupied by the tracks to be elevated and hold 85 in position the apron walls which are interlocked therewith and confine the fill. The piers admit of the use of a minimum amount of concrete in the apron walls for the reason that they transfer 90 from one apron wall to the other the horizontal pressure due to the fill, the weight of the traffic thereon, and the impact caused by the traffic moving over the tracks, the fill on the inside of one wall becoming a sustaining factor when the opposite wall is subjected to horizontal pressure.

For the ramps which are usually of considerable length and which lead up to the elevated tracks, I may employ the same method of elevating and the same track and fill supporting 95 structure composed of transverse piers and apron walls, but, generally, for the low portions of the ramps a further modification of my invention is put into effect, this modification involving gravity walls instead of apron walls, and pier sections which become an integral part of the completed structure for temporarily supporting the elevated track or tracks but not complete piers extending across the right-of-way.

This modified system, which is adaptable particularly for the ramps, I have shown in Figs. 12 to 15 for both a two-track and a four-track system. In this instance, transverse piers are erected along a portion of the length of the 100 tracks to be elevated substantially as hereinbefore described, and between the ends of these piers a gravity wall is erected along the outer side of the right-of-way. This gravity wall and the similar one along the opposite side of the 105 right-of-way are built of sufficient weight and width to sustain the fill and the load due to the traffic passing over it but are not connected by continuous piers extending from one wall to the other. The temporary track or tracks T⁸ will be erected on these piers as before until the fill 29 is made, after which the permanently elevated tracks T⁹ will be placed on the fill.

In Figs. 12, 13, and 14 the piers are shown extending inwardly from one of the gravity walls 110 only, but in the four-track system shown in Fig. 15 they extend inwardly from both gravity walls so that the two outer tracks T⁸ may be temporarily supported thereon while the intermediate track or tracks T¹⁰ can be left at their 115

lower level to take care of the usual traffic demands during the construction of the piers on which the two outermost tracks T^8 are temporarily supported. It will be understood, of course, that after the two outer tracks T^8 are temporarily supported on the piers 28, the intermediate track or tracks T^{10} will be removed, the fill will be made as in Fig. 13, and all the tracks permanently supported on the fill.

10 Instead of building a pier 28 as shown in these figures, i. e., interlocked with the gravity wall sections 27, the same results can be accomplished by superposing the piers on the back or inner side of the retaining wall. In either instance, the piers will form a supporting structure for the tracks while being elevated and they become an integral part of the finished structure.

This system is also adaptable where walls are to be constructed only on one side, as, for example, where there is a hill or sufficient right-of-way on the other side to support the fill or to provide the necessary width for the slope of the embankment on said other side.

Thus it will be seen that the objects of the invention are attained very effectively by the novel construction of piers formed in sections with apron walls erected between their ends and eventually extended entirely across the right-of-way so as to connect the two apron walls at intervals, or with gravity walls having piers extended inwardly therefrom but not entirely across the right-of-way to support the temporary elevated track or tracks, or, in some instances, with a single gravity wall only with its inwardly extending piers.

With my improved method of construction and track elevation in its various modified forms, the economies heretofore recited are effected but to the greatest extent however where the structure involves the apron walls with piers extended inwardly from these apron walls and built in sections to eventually form complete monolithic piers extending from one apron wall to the other.

45 While I have shown the preferred construction and certain modifications, I do not desire to be confined to the precise details of the method or the structures herein illustrated and described, as still other changes may be made, and I therefore aim in my claims to cover all modifications which do not involve a departure from the spirit and scope of my invention in its broadest aspects.

Having thus described my invention, I claim:

55 1. A structure for supporting railway tracks during elevating thereof and providing a retaining means for fill material after the tracks have been elevated, comprising a series of piers arranged at intervals lengthwise of the tracks and extending across the right-of-way, and apron walls constructed along the right-of-way between the ends of the piers and forming with the latter a series of box structures adapted to receive fill material.

65 2. A supporting structure for elevated tracks comprising a series of piers arranged at intervals lengthwise of the tracks and extending transversely of the right-of-way, and apron walls constructed along the right-of-way between the ends of the piers and forming with the latter a series of box structures adapted to receive fill material, the ends of the piers and the sections of the apron walls between the piers being interlocked.

75 3. A supporting structure for elevated tracks comprising a series of piers arranged at intervals

to extend transversely of the right-of-way and apron walls constructed along the right-of-way between the ends of the piers and forming with the latter a series of box structures adapted to receive fill material, the ends of the piers having shoulders and being recessed inwardly from the shoulders to receive the ends of the panels or sections of the apron walls.

4. A supporting structure for elevated railway tracks comprising a series of reinforced concrete piers arranged at intervals and extending transversely of the right-of-way, reinforced concrete apron walls constructed between the ends of the piers and interlocked therewith so as to prevent lateral movement of the apron walls but to admit of linear expansion and contraction thereof.

5. The method of elevating a series of railway tracks which comprises removing the outermost pair of tracks of the series, constructing pier sections at intervals crosswise of the right-of-way and extending inwardly from opposite sides thereof, erecting temporary elevated tracks thereon, forming retaining walls between the ends of the pier sections, removing the remainder of the tracks from between the pier sections, forming a fill between the walls and over the pier sections, and constructing the permanent elevated tracks thereon.

6. The method of elevating railway tracks which comprises, removing the track along one side of the right-of-way, erecting a series of pier sections extending inwardly from such one side of the right-of-way, temporarily supporting an elevated track thereon, constructing a retaining wall between the pier ends, removing the other track, completing the piers by extending them across the right of way and constructing a retaining wall between their ends at the opposite side of the right-of-way, forming a fill between the walls, and placing the elevated tracks thereon.

7. In a method of elevating a series of railway tracks the steps of constructing pier sections to extend inwardly from opposite sides of the right-of-way, temporarily supporting elevated tracks thereon, forming retaining walls between the ends of the pier sections and subsequently forming a fill between the walls and placing the elevated tracks thereon.

8. In a method of elevating a series of railway tracks the steps of forming pier sections to extend inwardly from opposite sides of the right-of-way, temporarily supporting elevated tracks thereon, constructing apron walls between the ends of the pier sections, completing the inner portions of the piers by constructing pier sections between the first named pier sections so as to form continuous piers, forming a fill in the space between the walls, and placing the elevated tracks thereon.

9. The method of elevating a series of railway tracks which comprises removing one or more tracks leaving one or more at their original level for traffic purposes, erecting transverse pier sections along the right-of-way at spaced intervals where the removed track or tracks were previously located, temporarily supporting one or more elevated tracks on said pier sections, removing the remaining track or tracks, completing the piers so that they will extend across the space originally occupied by the several tracks at their original level, providing retaining walls between the ends of the piers, supplying a fill between the retaining walls, and placing the elevated tracks on the fill.

10. In railway construction, a track, a series

of reinforced concrete piers arranged at intervals lengthwise of the track and extending across the right-of-way, an apron wall extending along the track and connected with the ends of said piers, and a fill supporting the track and retained in place by said wall.

5 11. In railway construction, a track, a series of reinforced concrete piers arranged at intervals lengthwise of the track and extending across the

right-of-way, an apron wall extending along the track and connected with the ends of said piers, and a fill supporting the track and retained in place by said wall, said piers being constructed and arranged to support the track for use during the building of said wall and the making of said fill.

6 HOWARD E. CULBERTSON.

CERTIFICATE OF CORRECTION.

Patent No. 2,160,399.

May 30, 1939.

HOWARD E. CULBERTSON.

It is hereby certified that error appears in the above numbered patent requiring correction as follows: In the heading to the drawings, Sheets 1, 2, and 3, line 4 thereof, for the filing date "July 3, 1939" read July 3, 1937; and that the said Letters Patent should be read with this correction therein that the same may conform to the record of the case in the Patent Office.

Signed and sealed this 25th day of July, A. D. 1939.
